UNITED STATES PATENT OFFICE.

JULIUS PHILIPP, OF NEW YORK, N. Y.

HAIR CLASP.

Application filed September 7, 1926. Serial No. 133,952.

This invention relates to improvements in hair fasteners, particularly to a clasp adapted to hold the hair in desired shape or arrangement, and it is the principal object of my invention to provide a hair clasp which by a simple manipulation will readily engage the hair and be kept in adjusted position therein to keep it neatly arranged in any desired manner.

Another object of the invention is the provision of a hair clasp of simple and therefore inexpensive construction, yet durable and efficient and positive in its operation.

A further object of my invention is the provision of a hair clip or clasp adapted to be provided with suitable ornaments such as rhinestones or the like and to be made of any suitable material such as aluminum, tortoise or the like, and of a suitable desired size and form.

These and other objects and advantages of my invention will become more fully known as the description thereof proceeds, and will then be more specifically defined in the appended claim.

In the accompanying drawing, forming a material part of this disclosure:

Fig. 1 illustrates the application of my novel and improved hair clasp to the head of a person.

Fig. 2 is a front elevation of a hair clasp constructed according to my invention.

Fig. 3 is an enlarged rear view showing a fragment of the clasp.

Fig. 4 is a section on line 4—4 of Figure 3.

Fig. 5 is a cross-section through the clasp on line 5—5 of Figure 3.

The clasp as illustrated in the drawing, consists of a body 10 of aluminum, tortoise or any other suitable material curved to suit the shape of a head, and having an upper bead 11 and lower teeth 12 provided in any number and having any desired convenient shape of metal or any other suitable material. Below the upper bead on the front face of the clasp a sliding plate 13 curved to snugly fit the curvature of the body 10 is arranged which is provided with a longitudinal slot 14 in which a peg or pin 15 projecting from the front wall of the body travels and which is provided with a suitable head engaging the outer face of the plate 13 to hold and guide the same during its displacement over the body.

An operating stud 16 is made integrally

with the plate 13 near one end thereof, and a similar stud 17 projects from the body 10 through the slot 14 near the other end of the body for limiting the movement of 60 the plate.

At the rear of the body a guide or casing 18 is provided in which a spring 19 or the like is arranged secured at its ends to suitable clips 20 of the body, or, as shown at 65 one end to one of the end clips 20 of the body and its opposite end to a small plunger 21 traveling within the guide 18.

The operation of my device will be entirely clear from the above description, if it is desired to arrange the hair in a certain manner and to hold the same in this arrangement, the comb teeth are engaged into the hair and the sliding plate is displaced laterally by the proper manipulation of knob 70 16 engaged by the index finger for instance, while the thumb engages the stud 17, if now the spring expanded by this manipulation contracts upon the release of the knob and stud, and the clasp is pressed firmly against 75 the head, it will engage the hair and be securely held therein to hold the hair as arranged. It will be understood that the casing or guide 18 is open at the rear to 80 let the spring engage the hair strands. 85

It is to be understood that while I have shown as an example the preferred form of my device, the same may be executed in practice in many other ways, and that the general arrangement of the device and the 90 construction of the minor details thereof may be changed within the scope of the appended claim without departure from the spirit and gist of my invention, so for instance the stud 16, and the stud 17 may be 95 provided at their outer ends with rhinestones or other precious stones or ornaments, and the comb or clasp itself may be ornamented in any desired manner without in any way to interfere with or deviate from 100 my above described invention.

Having thus described my invention, what I claim as new, and desire to secure by Letters Patent is:

A hair clasp of the class described comprising a body, an upper bead on said body, and lower comb teeth formed therewith, a sliding plate on the front face of said body having a longitudinal slot, means for holding and guiding said plate during its sliding movements relatively to said body, means for limiting the movements of said plate,

means for operating said plate to execute a sliding motion, a guide at the rear of said body, a spring in said guide, means for attaching the ends of the spring to said body for allowing an expansion of the same by the proper manipulation of the plate operating means, and a contraction upon the release of the same to engage the hair for

holding the clasp when pressed against the head in engagement with the hair and the latter in desired arrangement.

Signed at New York in the county of Bronx and State of New York this 4th day of September A. D. 1926.

JULIUS PHILIPP.
